UNITED STATES PATENT OFFICE.

GUSTAF MAGNUSON, OF MINNEAPOLIS, MINNESOTA.

COMPOSITION OF MATTER FOR CLEANING AND POLISHING WOOD OR METAL.

1,317,171.

Specification of Letters Patent. Patented Sept. 30, 1919.

No Drawing.

Application filed February 12, 1919. Serial No. 276,641.

To all whom it may concern:

Be it known that I, GUSTAF MAGNUSON, a citizen of the United States of America, residing at Minneapolis, in the county of 5 Hennepin, in the State of Minnesota, have invented a new and useful Composition of Matter for Cleaning and Polishing Wood or Metal, of which the following is a specification.

10 My composition consists of the following ingredients combined in the manner and proposition stated, viz:

Oil citronella 20%, butter of antimony 10%, peanut oil 10%, paraffin oil 40%, white 15 vinegar 10%.

These ingredients are to be thoroughly mingled by agitation.

In using the above named composition the 20 surface need not be entirely free from dust and dirt, because the composition serves double purposes of cleaning and polishing, the citronella oil making a harder, a brighter and a more lasting finish.

By the use of the above named composition the surface is thoroughly cleaned and 25

polished and a protecting covering added to the surface giving further wear and more luster.

While I have stated the proportions of ingredients which I consider to be the best 30 suited for the purposes described, I am able to obtain satisfactory results with a wide variation of proportions, and hence do not limit myself to the particular proportions as stated. 35

I claim:

1. The herein described composition of matter consists of oil citronella 20%, butter of antimony 10%, peanut oil 10%, paraffin oil 40%, white vinegar 10%. 40

2. The herein described composition of matter for cleaning and polishing wood or iron, varnished or painted or natural, consisting of: oil citronella, butter of antimony, peanut oil, paraffin oil, white vinegar. 45

GUST. MAGNUSON.
